UNITED STATES PATENT OFFICE.

PHILIP K. WILLIAMS, OF GLASTONBURY, CONNECTICUT, ASSIGNOR TO THE J. B. WILLIAMS COMPANY, OF GLASTONBURY, CONNECTICUT, A CORPORATION OF CONNECTICUT.

SOAP-STICK HOLDER.

1,257,436.

Specification of Letters Patent. Patented Feb. 26, 1918.

Application filed March 17, 1916. Serial No. 34,349.

To all whom it may concern:

Be it known that I, PHILIP K. WILLIAMS, a citizen of the United States, and a resident of Glastonbury, county of Hartford, 5 State of Connecticut, have invented certain new and useful Improvements in Soap-Stick Holders, of which the following is a specification.

The object of this invention is to provide 10 a soap stick holder and inclosing case of novel construction, the invention relating particularly to the means for securing the stick in the holder.

In the drawings—

15 Figure 1 is a sectional view of the holder on enlarged scale.

Fig. 2 is a similar view of a modification.

Fig. 3 is a separate view of the sleeve of the structure shown in Fig. 1.

20 Fig. 4 is a view of the sleeve and the bottom of the stick of the structure of Fig. 2, with the securing means removed.

Referring to Figs. 1 and 3, the holder comprises a cap *a*, a sleeve *b* removably se- 25 curable therein. The sleeve is preferably of tubular form, having intermediate its ends an annular shoulder *c* above which is a tubular portion *d* within which the end of the stick fits rather snugly, the exterior surface 30 of this upper portion being preferably knurled or roughened. Below the shoulder the sleeve fits into the cap, the securing means here shown being screw threads *e*.

In the embodiment of Figs. 1 and 3, the 35 portion of the sleeve below the shoulder is of larger diameter than that portion above the shoulder, and the end of the stick is shouldered as at *f*. The stick is insertible from the bottom of the sleeve, and its shoul- 40 dered end snugly fits within the enlarged lower end of the sleeve, the sleeve being then secured in the cap and the stick, seated and clamped against the transverse wall of the cap, being thus held against longitudinal 45 displacement relative to the sleeve. When the stick has been used up to the upper end of the sleeve, the sleeve may be removed from the cap, the base of the stick pushed out from the sleeve so that it may be en- 50 tirely used, thus eliminating any waste.

In the embodiment of the invention illus- 55 trated in Figs. 2 and 4, the sleeve may be quite like the sleeve of Figs. 1 and 3, but the stick instead of being shouldered is pro-

vided with a circumferential groove *h* near 55 its end, and after the groove end of the stick is fitted into the sleeve, some material of a nature which will set or harden may be poured while fluid into the lower end of the sleeve around the stick, filling the an- 60 nular space and forming a securing connec- 65 tion between the stick and the sleeve, as indicated at *h*. With this structure, when the stick is used up to the upper end of the sleeve, the sleeve may be removed from the cap, and with a pen-knife blade the inter- 70 locking material may be cut out so that the base of the stick can be withdrawn from the sleeve and used further. The details of construction of this embodiment of the in- 75 vention are reserved for another applica- 80 tion.

m denotes the box enveloping the stick and into the end of which the cap fits snugly, the box preferably being lined with a suit- 75 able material to prevent corrosion. The anular shoulder of the sleeve forms an abutment for the upper edge of the cap, and presents a smooth surface for engagement with the lining of the box, removing any 80 danger of the lining being frayed or torn by the repeated insertion of the cap into the open end of the box.

By this invention a firm support for the 85 stick is provided, but which will permit of the unused end of the stick being removed from the support, substantially eliminating any waste.

In accordance with the provisions of the 90 patent statutes, I have described the principle of operation of my invention, together with the apparatus which I now consider to represent the best embodiment thereof; but I desire to have it understood that the ap- 95 paratus shown is only illustrative, and that the invention can be carried out by other means.

I claim as my invention:

1. In a device of the character described the combination with a soap stick shoul- 100 dered at one end, of a sleeve provided with a tubular portion snugly fitting said stick and a shoulder engaging the shoulder of said stick, the part of said sleeve below said shoulder being threaded and shorter than 105 the shoulder part of said stick so that the latter projects beyond said sleeve, and a cap surrounding and having threaded engage-

ment with the lower end of said sleeve the end wall of said cap engaging the end of said stick.

2. In a device of the character described the combination with a soap stick shouldered at one end, of a sleeve provided with a tubular portion snugly fitting said stick and a shoulder engaging the shoulder on said stick, the part of said sleeve below said

shoulder being threaded and shorter than 10 the shoulder part of said stick so that the latter projects beyond said sleeve, a cap surrounding and having threaded engagement with the lower end of said sleeve the end wall of said cap engaging the end of 15 said stick, and an inclosing box engaging said cap.

PHILIP K. WILLIAMS.
